Primary Examiner — Lauren R Calve(74) *Attorney, Agent, or Firm* — Arc IP Law, PC; Joseph J. Mayo(57) **CLAIM**

The ornamental design for a sealable container, as shown and described.

DESCRIPTION

FIG. 1 is a front upper perspective view of a sealable container.

FIG. 2 is a bottom lower perspective view of the sealable container of FIG. 1.

FIG. 3 is a front view of the sealable container of FIG. 1.

FIG. 4 is a back view of the sealable container of FIG. 1.

FIG. 5 is a top view of the sealable container of FIG. 1.

FIG. 6 is a bottom view of the sealable container of FIG. 1; and,

FIG. 7 is a right side view of the sealable container of FIG. 1 of which the left side is a mirror image.

The broken lines in the drawings depict boundary lines between portions of the sealable container that form no part of the claimed design.
